UNITED STATES PATENT OFFICE.

ELLISON EDWARD VANDERHOEFF, OF JEROME, ARIZONA, ASSIGNOR TO AMERICAN MANGANESE STEEL COMPANY, OF CHICAGO, ILLINOIS, A CORPORATION OF MAINE.

DIPPER FRONT.

Application filed October 29, 1920. Serial No. 420,554.

To all whom it may concern:

Be it known that I, ELLISON EDWARD VANDERHOEFF, a citizen of the United States, residing at Jerome, in the county of Yavapai and State of Arizona, have invented certain new and useful Improvements in Dipper Fronts, of which the following is a specification.

My invention relates to fronts for dippers 10 for excavating, dredging and similar machines, and more particularly to fronts for dippers formed in a single piece from cast metal, preferably manganese steel.

An object of my invention is to provide a 15 single piece cast metal front for a dipper having a perfectly smooth interior portion and a plurality of ribs formed integrally therewith extending longitudinally of the front and cast on the outside of the front.

Another object of the invention is to provide a cast metal dipper front for dredge buckets and the like having the cutting edge reinforced to increase the life of the bucket, the reinforcing consisting in extending the 25 edge of the bucket beyond the seats for the dipper teeth.

Another object is to form a cast metal dipper front having the cutting edge spread or flared outwardly to aid in digging operations and to keep the bucket against the material being dug.

A further object is to provide a cast metal front for dippers the interior of which is smooth, and with reinforcing ribs on the 35 outside, with provision of means for additional reinforcement as occasion demands.

A still further object is to improve the construction of cast metal dipper fronts for successful commercial use.

Generally speaking, I carry out my invention by forming a dipper front of cast metal having a smooth interior, preferably of manganese steel, with the cutting edge flared or spread out at such an angle that will aid in digging. The cutting edge is provided with recesses which serve as seats for the dipper points, and I contemplate using reversible dipper points in connection with the cast metal front embodying this invention.

The above and other objects of my invention will be apparent from the drawings, wherein—

Figure 1 is a side elevational view partially in section, showing a front constructed

in accordance with the preferred form of the 55 invention;

Figure 2 is a front elevational view of the dipper front, showing two dipper tooth points in position;

Figure 3 is an enlarged view of a portion 60 of the front showing the application of a dipper tooth point thereto; and

Figure 4 is a side elevation of a dipper tooth as applied to a front constructed in accordance with my invention.

The dipper front of my invention is designated generally by the reference character 5 and, as usual, comprises the front portion with upstanding wings or side portions 5^a which may be secured by rivets or other fastening means to the body. In the drawings, I have provided a plurality of rivet holes 6 for securing the front to the dipper body. As will be observed from the drawings, the inside of the front of the dipper is smooth, 70 that is, there are no ribs nor shoulders on the dipper tooth points, nor other projections to catch dirt as the bucket is subjected to use. It is possible to discharge completely a bucket having a smooth interior leaving no 75 refuse whatsoever in the bucket. The digging lip of the bucket is spread or flared in order to form a digging or cutting lip which will aid in directing the bucket into engagement with the material being dug. I 80 have found that if the lip is spread about 10 degrees it will be sufficient for most purposes.

The edge of the cutting lip of the bucket is provided with a plurality of recesses 7 in line 90 with the ribs 8 formed on the outside surface of the front wall of the bucket. The recesses 7 are for the purpose of serving as seats for dipper tooth points 9, which, in the form shown, are of the reversible type. 95 The usual construction of reversible tooth points contemplates a web 10 joining the rearwardly extending jaws of the points to serve as means for preventing sidewise play of the points in service. To accommodate the webs 10 of the points the ribs 8 are recessed at 11 rearwardly of the seats 7 and suitable apertures 12 are provided which register with apertures in the jaws of the dipper tooth, so that rivets 13 or other 100 fastening means may pass through these apertures for securing the dipper teeth in place.

To receive the jaws 9^a of the dipper teeth, the tops and bottoms of the upper ends of the ribs 8 are recessed at 18 to permit the outer surfaces of the jaws to lie flush with the ribs. Shoulders or stops 19 are formed to abut the rear ends of the jaws 9^a to relieve the rivets from digging strains.

In order to reinforce certain portions of dipper fronts made in accordance with this invention, whenever found desirable I have provided means for attaching such reinforcements. These means include a plurality of rivet or bolt holes 14 passing through the ribs 8 of the dipper front, through which bolts 15 may pass for securing reinforcing bars 16 on the outside of the front which bars when worn may be replaced by new ones. The ribs extend backwardly overlying the heel of the front as at 17 to lengthen the life of the front. Such reinforcements take care of any thin portions in the front and prevent undue wear on parts of the front due to digging. The advantage of the reinforcing member 16 is especially noticeable in connection with larger buckets having a capacity of from six to twelve yards. These large buckets are used on very long booms and dipper sticks, so that it is difficult to secure the correct digging angle without rubbing the heel of the front, causing uneven wear on the outer surface thereof.

With a construction such as herein described, it is possible to prolong the life of a dipper front for the larger type of dippers and at the same time dig as efficiently as with the present type of bucket. In fact, digging with a bucket equipped with the front of my invention, it is possible to load and unload buckets faster, as the smooth interior prevents accumulation of dirt therein and the spread digging lip serves to direct the bucket into the material, rather than to direct it away from the digging.

By extending the digging lip beyond the seat of the digging point, it is possible to prolong the life of a bucket over that of the ordinary character, as excessive wear is experienced at the edges of the upper corner of the front and oftentimes these corners become worn, thus weakening the fronts and making necessary the employment of a new front. In dipper fronts wherein the digging edge lies back of the seats for the dipper points, the corners wear much faster, resulting in the discarding of dipper fronts much sooner than otherwise would be necessary. Where manganese steel is used in the manufacture of these fronts, the cost is very high, so that any means which makes possible the prolongation of the life of a dipper front of manganese steel is important. By my invention I have found that a dipper front made in accordance therewith outlasts

a dipper front of the ordinary kind many times, consequently the benefits to be derived from the use of such a construction are readily apparent.

While I have described more or less precisely the details of construction of my invention, I do not wish to be understood as limiting myself thereto, as I contemplate changes in form and the proportion of parts and substitution of equivalents as circumstances may suggest or render expedient, without departing from the spirit of my invention.

I claim:

1. A single piece cast metal front for excavating dippers having a plurality of longitudinally extending ribs formed integrally therewith and on the outer surface of the front, said ribs having seats at the upper ends thereof whereby a series of detachable dipper teeth may be secured to the ribs, the cutting edge of the front extending beyond said seats and being notched whereby said dipper teeth may lie flush with the ribs, and means for securing said teeth in place on said seats.

2. A dipper having a cast metal front, said front having a smooth surface on the inside of said dipper to permit complete discharge of said dipper, the other side of said front being provided with reinforcing ribs, said front having a cutting edge portion, said edge portion being recessed on the inside surface of said front and teeth mounted in said recesses in alignment with said reinforcing ribs.

3. A dipper having a cast metal front, said front having a smooth surface on the inside of said dipper to permit complete discharge of said dipper, the outside surface of said front having a plurality of longitudinally extending ribs, said ribs having recessed seats at the upper ends thereof and a series of detachable dipper teeth mounted in said seats and secured to said ribs, the cutting edge of the front extending beyond said seats.

4. A dipper having a cast metal front, said front having a smooth surface on the inside of said dipper to permit complete discharge of said dipper, the outside surface of said front having a plurality of longitudinally extending ribs, said ribs having recessed seats at the upper ends thereof, said front on its inside surface being provided with recesses communicating with said recessed seats, and a series of detachable dipper teeth secured to said ribs in said seats and recesses, the cutting edge of the front extending beyond said seats.

Signed at Jerome, Arizona, this 14th day of Sept., 1920.

ELLISON EDWARD VANDERHOEF.
